TRAVELING BLOCK

Lester C. Black, Los Angeles, Calif.

Application August 10, 1935, Serial No. 35,539

9 Claims. (Cl. 254—192)

This invention relates generally to tackle suitable for use in oil well drilling, in connection with conventional derricks. The subject matter disclosed herein is in part a continuation of my co-pending application Serial No. 31,023, filed July 12, 1935, and relates particularly to the construction of traveling blocks.

As set forth in the aforementioned co-pending application, tackle utilized in oil well drilling includes a crown block carried by the top or "water table" of the derrick, in conjunction with a traveling block. In the construction of both the crown and traveling blocks, it is now conventional practice to utilize sheaves journaled on central shafts, with load-transmitting members connecting the shafts to the derrick top for a crown block, or to the tool supporting clevis in the case of a traveling block. For a drilling operation to a moderate depth, such conventional tackle may give satisfactory service. However, the trend in recent years has been to operate at increased depths, until it is now common to drill to depths of from 9,000 to 10,000 feet. Drilling to such great depths has greatly increased hoisting loads on the tackle, and in addition hoisting speeds required have been increased. This is particularly true where rotary drilling apparatus is employed, which necessitates the removal and replacement of the entire string of drill pipes when the drilling bit is replaced.

In an attempt to meet the more severe requirements of present day drilling operations, equipment builders have continually increased the size of the crown and traveling blocks, without altering the general mode of construction employed. The problem has been complicated by the fact that cables of increased diameter are required for the deep well rotary drilling rigs, as for example a cable one inch and a quarter in diameter. With the present type of construction, equipment builders cannot employ sheaves sufficiently large in diameter to meet standard wire line practice, without re-design of the entire derrick, since the present crown and traveling blocks have been increased to such a size as to utilize all available space. Therefore, on installations now in use on deep well rotary drilling projects, the cables operate on sheaves which are considerably smaller in diameter than recommended for the cable employed, thereby greatly shortening the life of the cable.

Aside from the fact that present equipment builders have been unable to provide sheaves of a proper diameter for use with the heavy cables employed, their attempts to cope with the heavier

loads and greater hoisting speeds have resulted in crown and traveling blocks of excessive size which are cumbersome to handle. It is desirable to have a traveling block relatively short in length, since an excessively long block requires a taller derrick to properly rack the drill pipe. An increase in the thickness of both the crown and traveling blocks is even more serious. This is because the space between the center line of the derrick and the side on which the drill pipe is racked, is limited. Likewise, a relatively thick traveling block makes it necessary for the derrick man to swing the elevators beyond one side of the block, in order to attach them to the drill pipe, and the amount of such swinging movement is increased with an increase in thickness of the traveling block.

It is an object of the present invention to provide a traveling block for well drilling, which will avoid the disadvantages outlined above for a traveling block, of conventional design. The construction disclosed herein affords adequate load carrying capacity for deep well drilling, with sheaves of a proper diameter to operate with heavy cables, and at the same time the block is of reduced thickness and length.

Referring to the drawings:

Fig. 1 is a side elevational view of a traveling block incorporating the present invention, one-half of the block being shown in cross section. 30

Fig. 2 is a cross-sectional view taken along the line 2—2 of Fig. 1.

Fig. 3 is a perspective view, partly in cross-section, illustrating a modification of the block shown in Figs. 1 and 2. 35

Fig. 4 is a cross-sectional detail illustrating a further modification of the block shown in Figs. 1 and 2.

Fig. 5 is a side elevational view, in cross-section, showing a further modification. 40

Fig. 6 is an end view of the drum and sheave assembly incorporated in the modification of Fig. 5.

Fig. 7 is a detail showing one of the side plates incorporated in the modification of Fig. 5. 45

A particular feature of the traveling block constructed in accordance with my invention, is that it does not utilize conventional sheaves having spokes extending from a central hub. Instead of such conventional sheaves, I make use of rings of relatively large internal diameter, which are journaled on the outer periphery of a drum or like cylindrical structure. Thus, referring to Figs. 1 and 2, I employ a plurality of ring shaped sheaves 40, the outer peripheries of

- which are provided with grooves 11 to receive the hoisting cable. These sheaves are disposed in side-by-side relationship upon a cylindrically shaped drum 12.
- 5 In order to suitably journal the sheaves to the drum, and at the same time afford an interlock preventing lateral displacement, the inner peripheries of the sheaves are provided with grooves 13 to form ball-bearing races. The outer periphery of the drum 12 is likewise formed to provide spaced annular grooves 14. Balls 16 are disposed in the grooves or races 13 and 14, in order to properly journal the sheaves, and at the same time to lock the sheaves in their operating positions. The balls 16 are shown properly spaced by means of cages 17. In assembling the sheaves upon the drum, the balls are introduced into the races 13 and 14 through openings which are normally closed by plugs 18.
- 10 20 In order to form a low transmitting connection between the drum 12 and a lower tool clevis 21, a pair of side frame members 22 are provided. A suitable arrangement for attaching the clevis 21 to the lower extremities of frame members 22, is as follows: The frame members 22 have openings 23 in which the ends of the clevis bar 21 are accommodated. These openings are considerably longer than the corresponding dimensioning of the clevis bar 21, and the spaces 30 thus afforded above the clevis bar are normally occupied by the removal filler blocks 24. Lips 26 depending from the lower corners of the clevis bar serve to normally interlock with the frame members 22. However, when the filler blocks 24 are removed the clevis bar can be lifted to disengage it with respect to the frame members. Immediately above the lower portion of the drum 12, the frame members 22 are provided with inwardly extending trunnions 27, which are bored 40 to receive the connecting bolt 28. Removable locking blocks 29 can engage the heads of this bolt to prevent accidental loosening. On that portion of the drum adjacent to the trunnions 27, there is a saddle 31 in which the trunnions 45 27 rest, as shown in Fig. 2. The load transmitted to the drum by saddle 31 is distributed over a substantial lower segmental portion of the drum by means of webs 32.
- Near the upper portion of the drum 12 the side frame members 22 are connected together by bolt 33. This bolt is likewise attached to the drum by means of lugs 34, through which the bolt extends. However, this connection merely assists in maintaining the parts in assembled relationship and does not serve to transmit the main load between the clevis 21 and the drum.
- 50 55 The top of the block is provided with a clevis 36, which is suitably attached to the upper end of frame members 22. For example, a pair of bolts 37 can be provided, which extend through lugs 38 formed on the upper ends of the side frame members.
- To facilitate handling of the traveling block by an operator, suitable hand holds 41 can be 60 65 provided in the side frame members 22. It is also desirable to enclose the sheaves by means of suitable covers or housing sections 42 and 43, which are suitably attached to the side frame members.
- 70 75 Various modifications of the above described traveling block can be made within the scope of the invention. For example, as illustrated in Fig. 3, instead of forming bearing grooves directly in the periphery of drum 12, such grooves can be formed in a part or parts, which can be

removed or repositioned with respect to the drum. Thus in this instance separate grooved races 46 can be assembled on the drum 12, and locked to the drum by suitable means such as a key 47. In the event the lower segments of these races, 5 which carry the load, become worn, the races may be repositioned to present lower unworn segmental portions. As shown in Fig. 4 it is also possible to form the saddle 31 as a part separator with respect to the drum 12. Thus in this instance saddle 31a is a suitable casting or forging, which is secured to the drum by suitable means such as rivets or cap screws 48.

A further modification of the invention is illustrated in Figs. 5 to 7 inclusive, in which the provision for transmitting load to the drum is simplified. Thus in this instance the drum 51, which corresponds to the drum 12 of Figs. 1 and 2, is provided with annular flanges 52. The side plates 53, corresponding to the frame members 22 of Figs. 1 and 2, are made of sufficient width to entirely cover the ends of the drum 51. Each of these side plates is provided with an inwardly extending annular flange or rib 54, the outer periphery of which is machined to fit the inner periphery of the corresponding flange 51. The side plates are clamped to the drum by the upper and lower bolts 56. These bolts extend through lugs 57, which are carried by the drum flanges 52.

In the event, after a period of operation, the lower segmental portion of the drum becomes worn, the positioning of the drum with respect to the side plates can be shifted, by temporary removal of bolt 56. As shown in Fig. 6, it is 35 convenient to provide four sets of lugs 51, so that the drum can be shifted to angular increments of either 90 or 180°. It will also be evident in connection with this modification that in place of transmitting load through the trunnions 27 40 and saddle 31 of Figs. 1 and 2, the load is transmitted through the flanges 52 of the drum and the annular ribs 54. Thus the annular flanges 52 serve not only to reinforce the drum, but also serve to uniformly distribute transmission of 45 load to the drum over a relatively large segmental area.

The features and advantages of my traveling block will be apparent from the above description. The sheaves can be made to a diameter 50 adequate to handle heavy cable in conformity with practice recommended by cable manufacturers. The journals for the sheaves are capable of sustaining relatively heavy loads, due to the relatively large area over which the bearing load 55 is distributed. For a given number of sheaves the width of the block is far less than in conventional practice. This is because the sheaves can be made relatively thin, and because, by means of the type of journalling employed, they 60 can be maintained in closely assembled relationship without the use of supplemental spacing means between the sheaves. For a block of a given load and sheave capacity, the over-all length is at a minimum, thus making it possible 65 to manipulate the block more readily in various drilling and hoisting operations. In spite of the relatively short length of the block, twisting of the block during hoisting and lowering operations is not encountered to any detrimental degree, due to the reduced thickness, and to the fact that the load is transmitted between the clevis bar 21 and the drum 12, at a point well below 70 the axis of rotation of the sheaves.

I claim:

1. In a traveling block for oil well drilling, a plurality of ring-shaped sheaves, a hollow drum on which the sheaves are assembled in side-by-side relationship, means serving to journal the sheaves to the periphery of the drum, a load supporting clevis disposed below the sheaves, a saddle mounted on the lower inner peripheral portion of the drum, and trunnion means engaging said saddle and serving to transmit load from said clevis to said drum.
2. In a traveling block for oil well drilling, a plurality of ring-shaped sheaves, a hollow drum on which the sheaves are assembled in side-by-side relationship, means serving to journal the sheaves to the periphery of the drum, a load supporting clevis disposed below said sheaves, a pair of frame members disposed adjacent opposite ends of the drum, the lower ends of said frame members being attached to said clevis, a saddle mounted on a lower segmental portion of the drum, and trunnion means carried by said frame members and resting upon said saddle.
3. In a traveling block for oil well drilling, a plurality of ring-shaped sheaves, a hollow drum on which the sheaves are assembled in side-by-side relationship, a pair of frame members extending diametrically across the ends of the drum, a load supporting clevis secured to corresponding ends of said framing members below the sheaves and the drum, a saddle carried by a lower segmental portion of the drum, and a trunnion carried by said frame members and extending between the same, said trunnion resting upon said saddle, the axis of said trunnion being spaced a substantial distance below the axis of rotation of said sheaves.
4. In a traveling block for oil well drilling, a plurality of ring-shaped sheaves, the inner peripheries of the sheaves being grooved to form ball-bearing races, a hollow drum in which the sheaves are assembled in side-by-side relationship, the outer periphery of the drum having annular grooves forming ball-bearing races, ball bearings disposed in said grooves, said ball bearings serving to journal the sheaves to the drum and also serving to lock the sheaves in assembled side-by-side relationship upon the drum, a pair of frame members extending diametrically upon opposite ends of the drum, a load supporting clevis secured to corresponding ends of said framing members below the sheaves and the drum, a saddle mounted on a lower peripheral portion of the drum, and a trunnion secured to the frame members and extending between the same, said trunnion resting upon said saddle and having its axis disposed a substantial distance below the axis of rotation of the sheaves.
5. In a traveling block for oil well drilling, a plurality of ring shaped sheaves, a hollow drum on which the sheaves are assembled in side-by-side relationship, a pair of side plates extending over the end faces of the drum, annular portions formed on the drum and the side plates, said portions being interfitting, means securing the side plates to the drum, said means permitting angular shifting of the drum relative to the side plates through an angle of at least 180°, and a load supporting clevis secured to corresponding depending ends of the side plates below said sheaves.
6. In a block for oil well drilling, a plurality of ring-shaped sheaves, a drum on which the sheaves are assembled in side-by-side relationship, and means including ball bearings serving to journal the sheaves to the drum and also serving as the sole means to lock and maintain the sheaves in spaced assembled relationship upon the drum.
7. In a block for oil well drilling, a plurality of ring-shaped sheaves, a drum on which the sheaves are assembled in side-by-side relationship, the inner peripheries of the sheaves being grooved to form ball bearing races and the outer periphery of the drum having annular grooves likewise forming ball bearing races, and ball bearings disposed in said grooves, said ball bearings serving to journal the sheaves to the drum and also serving as the sole means to lock and maintain the sheaves in close spaced relationship upon the drum.
8. In a traveling block, a sheave assembly, a pair of side frame members secured to the sheave assembly, corresponding end portions of said frame members extending below the sheaves of said assembly and being provided with opposed openings, a load supporting clevis bar having its ends extending into said openings, the dimensioning of said openings in a vertical direction being substantially greater than the corresponding dimensioning of the bar, depending lips formed on the lower corners of the bar, and removable filler blocks disposed above the bar and serving in conjunction with the bar to fill said openings.
9. In a traveling block for oil well drilling, a plurality of ring-shaped sheaves, a drum on which the sheaves are assembled in side-by-side relationship, the inner peripheries of the sheaves being grooved to form ball bearing races and the outer periphery of the drum having annular grooves likewise forming ball bearing races, ball bearings disposed in said grooves, said ball bearings serving to journal the sheaves to the drum and also serving as the sole means to lock the sheaves in close spaced relationship on the drum, said drum being a one piece integral structure, a pair of framing members extending adjacent the ends of the drum, annular portions formed on the drum and the side plates, said portions being interfitting for transmitting load forces between the side framing members and the drum and being so formed as to enable the drum to be shifted at least 180° about its axis relative to the framing members, releasable means for locking the framing members to the drum, and a load supporting clevis secured to corresponding depending ends of the framing members below said sheaves.

LESTER C. BLACK. 65
